UNITED STATES PATENT OFFICE.

GEORGE C. CARSON, OF REDDING, CALIFORNIA, ASSIGNOR OF TWO-THIRDS
TO ALBERT MILLER, OF REDDING, CALIFORNIA, AND FRED HURST, OF
WASHINGTON, DISTRICT OF COLUMBIA.

CONVERTER.

SPECIFICATION forming part of Letters Patent No. 714,449, dated November 25, 1902.

Application filed December 17, 1901. Serial No. 86,327. (No model.)

To all whom it may concern:

Be it known that I, GEORGE C. CARSON, a citizen of the United States, residing at Redding, in the county of Shasta and State of California, have invented certain new and useful Improvements in Converters, of which the following is a specification.

My invention relates to apparatus for treating molten metals for converting metallic mattes into bullion or for converting molten pig into malleable iron or steel. For convenience in description and illustration I have shown the present invention as applied to the converter described in an application for patent filed by me August 30, 1901, Serial No. 73,816, although such improvements can be applied to other forms of converters used in connection with a smelting-furnace.

In the accompanying drawings, Figure 1 is a longitudinal section of a converter constructed substantially like the one described in the application referred to, but containing the present improvements. Fig. 2 is a cross-section on line $\alpha\alpha$ of Fig. 1.

The converter shown contains the compartments c , f , i , l , and m , separated by partitions and having the communicating ports or passages g , h , j , and l' . The blast-furnace is indicated at a , with its discharge-spout b over the compartment c , and d is the slag-spout from said compartment. Oxygen is supplied to the compartments c and i in the converter shown by tuyers z , which are carried horizontally through the converter-walls and which communicate with air headers or trunks s , extending along the sides. As it is desirable to supply such air in a heated condition, it has been usual to employ some external heating apparatus for bringing the air to the proper temperature. One part of my invention relates to the utilizing of the great heat of the molten metal in the converter for heating the air-supply previous to its admission to the tuyers. I accomplish this by forming an air-chamber in the hood v , which is supported above the converter in any suitable way, as by pillars or hangers, and which has an outlet or stack y at any convenient point. For this purpose I prefer the construction shown in Fig. 2, in which the hood has

double walls inclosing an air-space and which can be made in the arched form shown or in any other shape desired, provided that it be properly exposed to the heat below. The double walls should be braced and strengthened, and I have shown for that purpose longitudinal beams v' , bolted between the walls. An air-supply pipe q is connected to this heating-chamber, and hot-air-discharge pipes q' lead from it and communicate with the headers s . Thus the cold air supplied to the double-walled hood is heated by the molten metal under treatment, and external heating means are entirely done away with.

The double hood is provided with a hinged charging-door x , which is hollow and open at both ends. When open, such doors form chutes through which iron or steel scrap, oxide of lime, or other fluxes can be supplied to the converter as may be desired, Fig. 2.

Two doors are shown in Fig. 1, one in full and the other in dotted lines; but it will be understood that I do not limit myself to the number.

It will be seen that there is a slight space between the roof and the side walls of the converter. This permits the admission of air, the purpose of which will now be explained.

When the air-blast is turned on through the tuyers, among the reactions which take place is that of the oxygen uniting with the carbon in the proportion of one atom of oxygen to one of carbon to form carbon monoxid, which rises or is forced to the surface of the contents of the converter. Were a tight hood provided, this would pass off in that form to the open air through the exit from the hood; but by admitting air beneath the hood the carbon monoxid takes up additional oxygen from the air and is converted into carbon dioxide, the combustion due to the union producing an exceedingly hot flame, which fills the flame-space beneath the roof and heats the air within the air-chamber of the roof to a high degree.

By reference to Fig. 2 it will be seen that the cross-section of the converter is tapered downwardly—that is, that in cross-section its walls converge toward the bottom. This is for the purpose of protecting the tuyers z 100

and at the same time allowing them to project inwardly, so as to discharge practically at the point of greatest efficiency, which is the middle of the bath. It will be noted that 5 the twy whole in Fig. 2 do so discharge, but are embedded throughout their lengths in the converter-lining, whereby they are protected not only from the molten metal, but from heavy scrap, fluxes, &c., dumped into the 10 converter.

Of course my improvements can be applied to single-compartment converters or to any bath for molten metal provided with means for supplying air to the interior.

15 In converting copper matte, as well as other metallic mattes, the lining must be made of some suitable material that will be neutral to the metal under treatment, while the proper fluxes can be added at the doors of the hood 20 to give fluidity to the cinder.

There may be more than one charging-door α , as shown in Fig. 1, which illustrates one of said doors in dotted lines and one in full lines.

25 Having thus fully described my invention, what I claim as new, and desire to secure by Letters Patent, is—

1. In combination with a converter, twy whole for supplying air to the contents thereof, a 30 substantially dome-shaped roof above the same, said roof comprising inner and outer concentric walls, longitudinal I-beams separating and supporting said walls and having air-passages, an air-supply to the space between said walls, and a connection between said space and the twy whole, substantially as described.

2. In combination with a converter, a double-walled chamber above the same, and a 40 double-walled hinged door, forming when opened, a feed-chute.

3. A converter having primary and secondary chambers with downwardly-converging

walls, twy whole for forcing air into said primary and secondary chambers near the lower part 45 thereof, and an exit from said primary compartment to said second compartment below the line of the twy whole, substantially as described.

4. A converter having primary and secondary chambers with downwardly-converging walls, twy whole for forcing air into the primary and secondary chambers near the bottom thereof, a double-walled roof over said chambers forming an air-heating chamber, and connections from said air-heating chamber to said twy whole, substantially as described. 55

5. In a converter, a chamber having downwardly-converging walls increasing in thickness toward the bottom, and twy whole penetrating said walls and discharging into the contracted lower portion of the chamber, substantially as described. 60

6. In a converter, a chamber of substantially V shape, said chamber having its walls 65 thickened toward the bottom twy whole entering said walls and discharging into the chamber near the bottom, and a horizontally-extending exit for the molten metal at the apex of the chamber, substantially as described. 70

7. In a converter, the combination with the chamber for the molten metal and twy whole for admitting air thereto, of a double-walled roof over said chamber forming an air-heating chamber and a flame-space beneath, connections for conveying air from the heating-chamber to said twy whole, and an air-passage for admitting air to said flame-space beneath the roof, substantially as described. 75

In testimony whereof I have affixed my signature, in presence of two witnesses, this 16th day of November, 1901.

GEO. C. CARSON.
